UNITED STATES PATENT OFFICE.

EDWARD J. COLE, OF PEEKSKILL, NEW YORK.

CONSTRUCTION OF CORD TIRES.

Application filed March 5, 1924. Serial No. 697,099.

This invention relates to the construction of cord tires, the general object of the invention being to stretch the fabric to a degree equal to that to which it will be subjected when the inner tube in the completed tire is properly inflated and to permeate the fabric with rubber so that the cords are surrounded by rubber, thus eliminating friction, prevent stretching and renders peeling off of the rubber parts impossible.

Another object of the invention is to provide a pair of flaps at each edge of the fabric which are adapted to be folded around a rubber strip to form the beads of the tire.

Another object of the invention is to provide simple and effective means for stretching the fabric and forming the beads.

This invention also consists in certain other features of construction, and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view of an apparatus constructed in accordance with this invention.

Figure 2 is a section on line 2—2 of Figure 4.

Figure 3 is a section on line 3—3 of Figure 4.

Figure 4 is a section on line 4—4 of Figure 3.

Figure 5 is a section on line 5—5 of Figure 3.

Figure 6 is a transverse sectional view through the core parts and showing a tire thereon.

Figure 7 is a fragmentary view showing one of the core sections in lowered position.

Figure 8 is a transverse sectional view through one of the sections.

Figure 9 is a perspective end view of one of the sections.

Figure 10 is a view of part of the locking ring.

Figure 11 is a section on line 11—11 of Figure 1.

Figure 12 is a section on line 12—12 of Figure 7.

Figure 13 is a fragmentary view of a portion of the locking ring.

In these views, 1 indicates a supporting member which is mounted upon a shaft 2 which is supported by the uprights 3. The member 1 carries a set of hollow spokes 4 and a second set of hollow spokes 5, the second set being carried by the slides 6 which are arranged to slide in the member 1 and which are provided with arms 7 which have nuts 8 thereon which engage the screw threaded ends of the shafts 9 rotatably mounted in the supporting member 1 and which have pinions 10 thereon which are adapted to be engaged by a gear 11 connected with a sliding sleeve 12 supported by the shaft 2 and which has a gear 13 thereon adapted to be moved into mesh with a gear 14 on the power shaft 15 by a lever 16. Thus the spokes 5 can be moved longitudinally in the supporting member when desired. The spokes form bearings for the shafts 17 which are provided with threaded heads 18 on their outer ends for engaging the threaded interiors of the hollow members 19 which are adapted to be detachably connected with the core sections 20 and 21. As shown in Figure 12, the members 19 have their exteriors of square shape in cross section and the spokes 4 and 5 have also square exteriors with their interiors circular to receive the shaft 17. Beveled gears 22 are placed on the inner ends of the shafts 17 and these gears on the shafts in spokes 4 are adapted to engage the teeth on one face of the beveled gear 23 on the sliding sleeve 24 and the gears 22 on the shafts in the spokes 5 are adapted to engage the teeth on one face of the bevel gear 25 on the sliding sleeve 26, the sleeve 24 having a gear 27 on its outer end while the sleeve 26 has a gear 28 on its outer end, these gears 27 and 28 being arranged to be moved into mesh with the gears 29 on the power shaft 15 by the levers 30 and 31. The core sections 20

are supported by the parts carried by the spokes 4 while the sections 21 are supported by the parts carried by the spokes 5 so that these sections 21 can be moved not only radially as can the sections 20 but they can also be moved longitudinally of the supporting member 1 and from under the sections 20 so as to permit these sections 20 to be moved inwardly to their full extent. The sections 21 are of wedge shape so as

to fit between the sections 20 and the ends of the sections 21 have wedge-shaped projections 32 thereon for engaging recesses 33 in the ends of the sections 20 and all the sections are provided with longitudinally extending grooves 34 in one side for receiving a sectional locking ring 35 for holding the sections together. The abutting ends of the sections of the ring are held together by the pins 36 and one section is provided with a curved tongue 37 for engaging a curved recess formed in one of the sections 20 when the locking ring is given a partial rotary movement. The other section of the locking ring is held in position by means of a screw 38 passing through an ear 39 on said section and entering one of the sections 20.

The bead forming flanges 40 are connected by the brackets 41 with the interiorly screw threaded members 42 which are similar to the members 19. These members 42 are engaged by the threaded heads of the shafts 43 which are carried in the bearings 44 supported by the slides 45 in the member 1, the slides having nut parts 46 thereon which engage the threaded portions of the shafts 47 mounted in the member 1 and which have pinions 48 at the outer ends which are adapted to mesh with the gear 49 formed with the gear 11 and which is adapted to be moved into mesh with the gear 50 on the power shaft by the lever 16. The shafts 43 have the bevel gears 51 on the inner ends which are designed to mesh with the teeth on the outer faces of the gears 23 and 25 when the levers 30 and 31 are moved to slide the sleeves 24 and 26 to place the gears 23 and 25 in mesh with the gears 51. The levers 16, 30 and 31 are held in their adjusted positions by means of the notches 52 engaging the keeper bar 53.

The cord fabric is provided with a pair of flaps 54 and 55 at each edge and these flaps are folded about the strips 56 to form the beads of the tire and a pair of rings 57 is placed on the mold to receive the inner edges of the beads. These rings cooperate with the bead molds 40 to form the beads and after the parts have been brought into molding position they are fastened together by the bolts 58 so that the partially formed tire and the mold can be removed from the stretching apparatus and the tire finished in the usual manner.

From the foregoing it will be seen that by manipulating the levers 16, 30 and 31 the sections 21 can be moved inwardly and then longitudinally of the member 1 so that they will be out of the way of the sections 20 when these sections are moved inwardly. This will permit the cord fabric to be placed on the mold and then the parts can be returned to normal position to stretch the fabric. The bead molding parts are then moved in-

wardly to form the beads, the locking ring being first put in position to hold the sections 20 and 21 in stretched position.

This invention will produce a tire from a one cord carcass, the cord fabric being in mesh form and stretched by the device to a degree equal to that to which it will be subjected when the inner tube is properly inflated in the completed tire. This will open the meshes and when the rubber parts are built upon it it will become permeated with rubber. The fabric is woven several sizes smaller than the regular tire size and it is woven with a larger sized cord at the tread and reduced in size as it meets the side walls. It is the same at both sides and its edges are provided with two flaps for enclosing the bead forming strips. The cord fabric is permeated with rubber before it is stretched over the mold.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A tire forming apparatus, comprising a tubular support having guideways therein, two sets of radiating spokes carried thereby, one set of spokes being mounted to move in the guideways, shafts carried by the spokes, each shaft having a screw threaded head, an interior screw threaded member engaging each head, means for rotating the shafts, a sectional core of ring shape, each section being carried by a threaded member, means for locking the ends of the sections together when the core is expanded, a ring member engaging the sections for locking them in expanded position and means for moving the one set of spokes in the guideways.

2. A tire forming apparatus, comprising a tubular support having guideways therein, two sets of radiating spokes carried thereby, blocks slidably mounted in the guideways and carrying one set of spokes, means for moving the blocks in the guideways, shafts carried by the spokes, each shaft having a screw threaded head, an internally screw threaded member engaging each head, means for rotating the shafts, a sectional core of ring shape, each section being carried by a threaded member, the sections having beveled ends, some of the sections having recesses in their ends, pins on the ends of the other sections engaging the recesses and a ring member engaging the sections for locking them in expanded position.

3. A tire forming apparatus, comprising a tubular support, two sets of radiating spokes carried thereby, means for moving

one set longitudinally of the support, threaded shafts carried by the spokes, an internally threaded member engaging the screw threaded part of each shaft, means for rotating the shafts, a sectional core of ring shape, each section being carried by a threaded member, means for connecting the ends of the sections together when in expanded position, a ring member for locking the sections in expanded position, the sections being grooved to receive the ring member and means for detachably connecting the ring member to some of the sections.

4. A tire forming apparatus, comprising a tubular support, two sets of radiating spokes carried thereby, means for moving one set longitudinally of the support, threaded shafts carried by the spokes, an internally threaded member engaging the screw threaded part of each shaft, a sectional core of ring shape, each section being carried by a threaded member, means for rotating the shafts, bead forming members, supports for the same, means for moving the supports longitudinally of the tubular support and means for adjusting the length of the supports so that bead forming members of different sizes can be used with the device.

5. A tire forming apparatus, comprising a tubular support, two sets of radiating spokes carried thereby, means for moving one set longitudinally of the support, threaded shafts carried by the spokes, an internally threaded member engaging the screw threaded part of each shaft, a sectional core of ring shape, each section being carried by a threaded member, means for

rotating the shafts, bead forming members, tubular members carrying the same and having interior screw threads, a threaded shaft engaging the said threads of each member, means for moving the said shafts longitudinally of the main support to move the bead forming members toward and away from the core and means for rotating the shafts of the bead forming members.

6. A tire forming apparatus, comprising a tubular support having guideways therein, blocks slidably mounted in the guideways, means within the support for moving the blocks, a plurality of spokes radiating from the support and one set of which is carried by some of the blocks, bearing members carried by the other blocks, a threaded shaft carried by each spoke and each bearing member, an internally threaded member on each shaft, bead forming members carried by the threaded members on the shafts in the bearing members, a sectional core of ring shape having its sections carried by the threaded members on the shafts in the spokes, means for locking the sections of the core together in expanded position, means within the tubular support for rotating the shafts of the core, means within the tubular support for rotating the shafts of the bead forming members, a drive shaft and manually controlled means for connecting the block shifting means and the two sets of means for rotating the different shafts to said drive shaft.

In testimony whereof I have affixed my signature.

EDWARD J. COLE.
